K. BERGER

SNATCH BLOCK

Filed Aug. 2, 1926

FIG. 1.

FIG. 2.

FIG. 3.

INVENTOR
Knute Berger
BY
Frank Warren
ATTORNEY

UNITED STATES PATENT OFFICE.

KNUTE BERGER, OF SEATTLE, WASHINGTON.

SNATCH BLOCK.

Application filed August 2, 1926. Serial No. 126,607.

My invention relates to improvements in snatch blocks and the object of the invention is to provide a snatch block comprising two U-shaped frame members pivotally held together in such fashion that a dog pivoted to one member serves to prevent the line from disengagement with the sheave carried by the other member and also serves as a stud spacer to counteract heavy strains that would tend to collapse said frame members. Further objects are to provide simple means for removing the lines by pivotal movement of the smaller U-shaped member carrying the pivoted dog out of engagement with the larger U-shaped member.

With the above and other objects in view which will appear as the description proceeds, the invention consists of the novel construction, adaptation, combination and arrangement of parts hereinafter described and claimed. I accomplish these objects by devices illustrated in the accompanying drawings, wherein:

Figure 1 is a view in elevation showing a tackle block embodying the features of the invention;

Fig. 2 is a view in elevation showing the method of pivotally opening the device and removing the lines therefrom; and

Fig. 3 is a view in horizontal section taken substantially on line 3, 3 of Fig. 1.

Referring to the drawings throughout which like reference numerals designate like parts, the numeral 5 indicates a relatively large, substantially U-shaped lower member that is provided with a sheave 6 rotatively mounted on a stud axle 7. A relatively small U-shaped upper member 8 is pivotally secured to said large U-shaped member 5 by a pivot pin 9. As shown in Fig. 1 said members may be locked together in the closed position by a pin 10 passing through eyes 11 and 12 respectively in said members.

The opening between the legs 25 of the lower member 5 is enlarged adjacent the periphery of the sheave 6 to form a substantially triangular slot 13 with rounded corners in conjunction with the groove in said sheave. A dog 14 pivoted at 15 to the upper member 8 is provided at one end with an enlarged head portion 16 that serves as a closure for said triangular slot when the device is in the closed position.

Besides serving as a closure for the slot 13 the head portion 16 of the dog 14 also serves as a means for retaining the legs 25 of the

lower member 5 in spaced relation to prevent heavy strains from drawing said legs together as more fully hereinafter set forth. As clearly shown in Fig. 3 of the drawings 60 the head of said dog is provided with spaced flanges 17 that overlap projections 28 disposed on said legs 25 and retain the dog in snug engagement therewith.

A bight of a line 18 may be passed through 65 the loop of the lower member 8 for fastening the device to any desired stationary object. A running line 19 may be passed around the sheave 6 for pulling the load fastened thereto. The device is designed for moving heavy 70 objects and it will be obvious that the longitudinal strain caused thereby would tend to draw the legs of the lower and upper members 5 and 8 together causing said sheave to jam and ultimately causing the legs 25 to 75 collapse. To offset this tendency the dog 14 is adapted to hold said legs in proper spaced relation against all strains.

When the device is in the closed position the line 19 cannot escape from the sheave 6 80 by reason of the head of the dog 14 serving as a closure for the triangular slot 13. The corners of said slot are rounded to prevent chafing of said line and even though the line should become slack and slip out of the 85 groove in the sheave said triangular slot will always serve as a guide to direct the line 19 back to the sheave whenever said line again becomes taut and the bight of the line 18 is confined within the space above the head 90 of the dog 14 thereby preventing the lines from interfering with one another.

Referring to Fig. 2 of the drawings, whenever it is desired to disconnect the lines from the device it is merely necessary to 95 remove the pin 10 when the member 8 may be swung outwardly carrying the dog 14 therewith and leaving both U-shaped members open between their legs for withdrawal of the lines. This feature has a distinct 100 advantage in the fact that the bight of the running line 19 may be slipped off without the necessity of reeving in to its end which is usually of considerable length. When the device is open the bights of both lines 105 may, of course, be as readily and conveniently installed, and upon closing the members the dog will slide easily into position by reason of its pivotal connection.

Although I have described the device in 110 considerable detail it will be understood that I intend no limitations except in so far as

may be imposed by the appended claims, and that I reserve the right to resort to such changes as do not depart from the scope and spirit of the invention.

5. What I claim is:—

1. A snatch block comprising two substantially U-shaped members, the adjoining legs of said members secured together on one side for pivotal movement, means for locking the adjoining legs together on the other side, a sheave rotatively carried by one of the members, said sheave carrying member having an enlarged slot adapted to guide a running line into engagement with the sheave, a dog pivotally connected to the other member, and adapted to serve as a
- 10
- 15

closure for said slot and as a means for retaining the legs of the U-shaped members in spaced relation.

2. A snatch block comprising an upper member and a lower member pivotally connected, legs on said lower member having projections thereon, means for locking said members together, a dog pivoted at one end to said upper member the other end being provided with a head having spaced flanges that are adapted to overlap said projections on said lower member, and a sheave carried by said lower member.

- 25

In witness whereof, I hereunto subscribe my name this 20th day of July A. D. 1926.

KNUTE BERGER.
